His Attorney.

UNITED STATES PATENT OFFICE.

WILLIAM M. MYERS, OF ST. JOSEPH, MISSOURI.

WRENCH.

1,406,408.

Specification of Letters Patent. Patented Feb. 14, 1922.

Application filed May 28, 1920. Serial No. 384,845.

To all whom it may concern:

Be it known that I, WILLIAM M. MYERS, a citizen of the United States, residing at St. Joseph, in the county of Buchanan and State 5 of Missouri, have invented a certain new and useful Improvement in Wrenches, of which the following is a specification.

My invention relates to improvements in wrenches. It relates particularly to monkey 10 wrenches.

The object of my invention is to provide a wrench of the kind described, which is simple in construction, cheap to make, durable and not liable to get out of order, and 15 which can be easily and quickly adjusted to and from the gripping position.

The novel features of my invention are hereinafter fully described and claimed.

In the accompanying drawing, which illustrates the preferred embodiment of my invention,

Fig. 1 is a view partly in side elevation and partly in vertical section of my improved wrench.

Fig. 2 is a side elevation of the same.

Fig. 3 is a cross section on the line 3—3 of Fig. 1.

Fig. 4 is a cross section on the line 4—4 of Fig. 2.

Similar reference characters designate similar parts in the different views.

1 designates the shank of the wrench having a fixed jaw 2, toward and from which is adapted to be slid, on the shank 1, a 35 slideable jaw member 3 having a jaw 4 adapted to co-operate in the usual manner with the fixed jaw 2.

A handle 5 is pivoted on a transverse bolt 6 mounted in the shank 1 and having at one 40 end a head and at the other a threaded longitudinal hole 7 in which is fitted a securing screw 8, Fig. 4, having a head which bears against the handle 5.

A flat spring 9 secured to the adjacent end 45 of the shank 1 bears against the inner side of the handle 5 and normally forces the latter to an initial position from which it is swung by hand when the wrench is used to grip a pipe, nut or bolt.

Slidable on the shank 1 is a member 10 50 having on its outer edge a longitudinal row of teeth 11 which are preferably ratchet teeth. The middle portion of the member 10 has a transverse slot 12, Fig. 1, through 55 which extends a loosely fitted pin 13 mounted in the handle 5. The outer end of the

member 10 is slightly rounded and fitted to bear against a shoulder 14 in the lower portion of the handle 5. The latter has a longitudinal slot at the inner side of the shoulder 60 14 adapted to receive the lower portion of the member 10.

When the handle 5 and member 10 are compressed with the hand, it will effect a swinging to the left of the handle 5 and an inward sliding movement of the toothed member 10 on the shank 1. This is for the purpose of moving the sliding jaw 3 from close to a gripping position to a gripping position. 70

To move the jaw 3 to the approximate gripping position, there is mounted in a recess 15 in the movable jaw 3, a pawl 16, which is pivoted by a transverse pin 17 to the jaw member 3. A flat spring 18 attached to the 75 pawl has its free end bearing against the member 3, so as to force teeth, with which the pawl 16 is provided, into locked engagement with the teeth 11 of the member 10.

When the handle 5 and member 10 are 80 compressed with the hand, the handle will be swung to the left and the member 10 will be slid inwardly, thereby moving the jaw 3, through the intermediacy of the pawl 16 to the gripping position. 85

Upon releasing the compression against the member 10 and handle 5, the spring 9 will swing the handle 5 to the right, thus drawing outwardly slightly the toothed member 10, thereby releasing the movable 90 jaw 3, so that the wrench may be turned on a pipe to take another bite, or removed from a nut or bolt head to take a new grip thereon.

To release the pawl 16 from the member 95 10, so that the jaw 3 may be quickly slid to or from any given position, I provide a thumb operated lever 19 pivoted on a transverse pin 20 to the jaw member 3. The inner end of the lever 19 is mounted in a 100 transverse groove 21 in the outer end of the pawl 16.

In the operation of my invention, one hand of the operator grips the handle 5, the thumb of that hand being employed to 105 swing to the right the outer end of the lever 19, thereby detaching the pawl 16 from the teeth 11, upon which the thumb can slide the jaw 3 to an approximate operating position, in which position, the object to be turned 110 with the wrench will be disposed loosely between the jaws 2 and 4. The operator then

compresses the handle 5 and member 10, thereby swinging the handle 5 to the left, the handle by means of the shoulder 14 forcing the member 10 and with it the pawl 16 and jaw 3 slightly inwardly, so that the object between the jaws 2 and 4 will be tightly gripped, after which the wrench may be swung to the left to turn the object. If the object is to be turned in the other direction, 10 the wrench is reversed and is swung to the right.

After the pulling strain on the handle 5 is removed, the spring 9 will swing the handle to the right, thus loosening the jaw 3 from 15 the object gripped, after which the wrench may be turned to take a new bite and the operation above described, repeated.

I do not limit my invention to the structure shown and described, as many modifications, within the scope of the appended 20 claims, may be made without departing from the spirit of my invention.

What I claim is:—

1. A wrench having a shank provided 25 with a fixed jaw, a handle pivoted to the shank, a jaw slidable on the shank, a member adapted to be grasped by the hand with the handle and engaging the handle and movable thereby toward the fixed jaw when 30 the handle and member are compressed and one moved toward the other, and releasable

means for locking the slidable jaw and said member together, substantially as set forth.

2. A wrench having a shank provided 35 with a fixed jaw, a handle pivoted to the shank, a jaw slidable on the shank, a toothed member pivoted to the handle and adapted to be compressed with the handle by the hand and reciprocative toward and from the fixed jaw when the handle is swung toward and 40 from the toothed member, and a spring for forcing the handle from the toothed member, and a pawl carried by the slidable jaw and arranged for releasable engagement with the toothed member. 45

3. A wrench having a shank provided 50 with a fixed jaw, a handle pivoted to the shank, a jaw slidable on the shank, a toothed member having means for engagement with the handle by which the toothed member is moved toward and from the fixed jaw when 55 the handle is oscillated on the shank, the toothed member and handle being adapted to be grasped with one hand and compressed thereby so as to swing the handle toward the toothed member, and a pawl releasably engaging the toothed member, substantially as set forth.

In testimony whereof I have signed my name to this specification.

WILLIAM M. MYERS.
